CLAIM

The ornamental design for a pair of vehicle rear doors, as shown and described.

DESCRIPTION

FIG. 1 is a left upper perspective view of a pair of vehicle rear doors, in use condition showing my new design;

FIG. 2 is a left side elevational view thereof;

FIG. 3 is a rear side elevational view thereof;

FIG. 4 is a forward elevational view thereof;

FIG. 5 is a rearward elevational view thereof;

FIG. 6 top plan view thereof; and,

FIG. 7 is a bottom plan view thereof.

The dash-dash even broken lines illustrate and surround portions of the pair of vehicle rear doors that form no part of the claimed design. The “long dash-short dash-short dash” broken lines shown in the drawings illustrate vehicle environmental subject matter which forms no part of the claimed design. The other of the pair of vehicle rear doors, having a mirror image, is not separately illustrated in the drawing views.
